DESIGN FOR A POULTRY SHACKLE

Frank J. Bilek, Chicago, Ill., assignor to The
Globe Company, Chicago, Ill., a corporation of
Illinois

Application September 25, 1944, Serial No. 115,451

Term of patent 14 years

(Cl. D12—2)

To all whom it may concern:

Be it known that I, Frank J. Bilek, a citizen of the United States, residing at Chicago, in the county of Cook and State of Illinois, have invented a new, original, and ornamental design for a Poultry Shackle, of which the following is a specification, reference being had to the accompanying drawing, forming a part thereof.

Figure 1 is a perspective view of the poultry shackle embodying my new design;

Fig. 2 is a front elevational view of the shackle shown in Fig. 1; and

Fig. 3 is a side elevational view of the shackle shown in Fig. 1.

The characterizing features of my new design reside in the configuration of the shackle as shown in full lines.

I claim:

The ornamental design for a poultry shackle, substantially as shown and described.

FRANK J. BILEK.
